UNITED STATES PATENT OFFICE

ANDRÉ PERUGIA, OF PARIS, FRANCE

DESIGN FOR A SHOE

Application filed November 4, 1929. Serial No. 33,304. Term of patent 7 years.

To all whom it may concern:

Be it known that I, ANDRÉ PERUGIA, subject of the Italian Kingdom, residing at Paris (Seine), France, 11 Faubourg St.-Honoré, have invented a new, original, and ornamental Design for a Shoe, of which the following is a specification, reference being had to the accompanying drawing, forming part thereof.

Fig. 1 is a side elevation of a shoe, showing my new design.

Fig. 2 is a plan view of the lower quarters of the shoe shown in Fig. 1 on an enlarged scale.

I claim:

The ornamental design for a shoe, as shown.

ANDRÉ PERUGIA.
